UNITED STATES PATENT OFFICE

119,204

DESIGN FOR A STENOTYPE MACHINE

William B. Petzold, Pittsfield, Mass., assignor to
General Electric Company, a corporation of
New York

Application October 24, 1939, Serial No. 87,832

Term of patent 14 years

To all whom it may concern:

Be it known that I, William B. Petzold, a citizen of the United States, residing at Pittsfield, in the county of Berkshire, State of Massachusetts, have invented a new, original, and ornamental Design for a Stenotype Machine, of which the following is a specification, reference being had to the accompanying drawing, forming a part thereof.

Figure 1 is a front perspective view of a stenotype machine showing my new design.

Figure 2 is a rear perspective view thereof, to a somewhat reduced scale.

The dominant features of my design reside in the portions shown in solid lines.

I claim:

The ornamental design for a stenotype machine, as shown and described.

WILLIAM B. PETZOLD.
